COMPRESSOR

George R. Lyon, Highland Park, Mich.

Application March 4, 1938, Serial No. 193,986

5 Claims. (Cl. 230—180)

This invention relates to an improvement in pumps and more especially, pumps for pumping liquids and compressing gases in which two pistons operate in a single cylinder.

One of the objects of this invention is the provision of a pump functioning without valves in which opposed pistons operating in a single cylinder control the supply and distribution of the fluid handled.

10 A second object of this invention is the provision of a pump of the type set forth in the preceding paragraph in which the opposed pistons are actuated by rods from cranks which operate at the same speed and have different throws.

15 It is another object of the present invention to regulate the speeds and paths of travel of the opposed pistons in relation to each other and in coordination with respect to the inlet and outlet ports, whereby the optimum displacement is achieved and the two pistons are prevented from interfering with one another.

20 A further object of this invention is the provision of a pump of the type set forth in the preceding paragraphs, which, because of its simplicity of design, is capable of a wide range of uses in the pump and compression field.

Additional objects and advantages of this invention will be more apparent as the description 25 proceeds, wherein,

Figure 1 is a horizontal sectional view of a pump taken along the line 1—1 of Figure 2.

Figure 2 is a sectional elevational view taken along line 2—2 of Figure 1.

30 Figure 3 is a diagram showing one complete cycle of the operation of the pump.

Figure 4 is a sectional plan view of a modification of the pump shown in Figures 1 and 2.

Figure 5 is a sectional side elevational view of 35 the modified structure taken on lines 5—5 of Figure 4.

Figure 6 is a curve showing a characteristic cycle of the piston-functioning of the modification shown by Figures 4 and 5.

With reference to Figures 1 to 3, there is shown 40 a cylinder 10 having therein an inlet port 11 and a discharge port 12. Located within this cylinder are opposed pistons 13 and 14 connected to cranks 15 and 16 by rods 17 and 18. Crank 16 is provided with means for receiving suitable motivating power and this motion is transmitted to crank 15 by means of side cranks 19, 20, 21, and 22, which are connected by links 23 and 24, herein-after more fully described.

With special reference to Figure 3, the opera-

tion of the pump is as follows: In this figure, four sets of numerals from 0 to 35 have been set out. Those numerals below X—X represent the different positions of piston 14 and the set above line X—X represent the different positions of piston 13. Thus, by comparison of similar numerals, the relative location of the pistons and the relative location of the cranks may be accurately determined and compared, throughout the cycle. The adjoining faces of the pistons are in essential contact when the movements of the pistons are in the direction from the discharge port 12 towards the inlet port 11, as shown by 5 O—O in Figure 3. At this point piston 13 covers and closes the discharge port 12. With continued 10 movement of the pistons toward the inlet port 11, the velocity of the piston 14 accelerates more rapidly than that of piston 13 because of the relative position of the crank centers 25 and 26 in their rotative paths and because of the difference 15 between the lengths of the cranks 15 and 16. Thus, depressed pressure of partial vacuum is created between the pistons. With continued 20 movement, separation of the pistons increases and at the passage of piston 14 over the inlet 25 port 11, as at 10, (below X—X) of Figure 3, the fluid from the inlet connection will be caused to flow into the space between the pistons. The pistons continue to separate with the inlet port 11 open, piston 13 then reaching the end of its 30 stroke and reversing its direction as at 11 (above X—X) of Figure 3, followed by the same action on the part of piston 14 as at 15 (below X—X) of Figure 3. The rate of separation of the pistons then gradually decreases until they momentarily 35 attain equal velocity at the point at which piston 14 completely closes inlet port 11 in its return stroke, as at point 20 (below X—X) of Figure 3. The space between the pistons then decreases as both travel toward the discharge port 12, compressing 40 the contents of the cylinder.

With continued movement of piston 13, the discharge port is opened, as at point 22 (above X—X) of Figure 3. As piston 13 reverses at the end of its travel beyond the discharge port, piston 45 14 continues to approach that port which it partially covers and then reverses, as at point 35 (below X—X) of Figure 3. Piston 13 overtakes piston 14 just as the velocities become equalized momentarily, which is at the point where piston 50 13 covers the discharge port and thus completely ejects the contents of the space between the pistons and completes the cycle.

With additional reference to Figures 1, 2, and 55 3, more in detail, it will be seen that cylinder

10 has an inner wall 27 and an outer wall 28 and located between are chambers 29 for circulation of a suitable cooling medium. The cylinder is also provided with annular spaces 30 and 31, therein communicating with the interior of the cylinder by means of inlet and discharge ports 11 and 12. Although not shown, it is to be understood that suitable connections extending from the source of supply and point of delivery will be provided at the exterior openings of inlet and discharge annular spaces 30 and 31. Secured to the piston 14 by means of wrist pin 34 is the forward portion of rod 18. The rearward portion of rod 18 is connected to crank 16 by bearing cap 32. Rod 17 has its forward portion connected to piston 13 through the medium of wrist pin 33 and the rearward portion of this rod is connected to crank 15 by bearing cap 35. Cranks 15 and 16 have their ends 52, 53, 54, and 20 55 seated in bearings 62, 63, 64, and 65, formed at the end of cylinder 10.

It will be noticed that crank 16 has a greater depth than crank 15 and as herein shown the diameter of circle of travel of crank 16 is approximately one third greater than the circle of travel of crank 15. This is done to impart a greater throw to piston 14 than to piston 13 and makes the path of travel of piston 14 also approximately one third farther than the path of travel of piston 13. In addition to the difference of the diameter of the path of travel between cranks 15 and 16, there is an additional difference in that crank 16 is also provided with a gear wheel 39 which is connected to suitable motivating 35 power.

At the end 52 of crank 16 there is provided a side crank 40 and at the end of 53 of crank 15, is provided a side crank 41. These two side cranks are connected to each other by link 23. The opposite ends 54 and 55 of cranks 15 and 16 are also provided with side cranks 42 and 43 which in turn are connected by link 24. These side cranks are positioned so that those on one side will be ninety degrees in advance of those on the opposite side, thus causing delivery of uniform turning effort from crank shaft 16 to crank shaft 15, and rotation of the two crank shafts is positively synchronized. It will, of course be understood in this connection that I do not desire to limit myself to the particular driving means, to wit, side cranks and links herein disclosed. Obviously, other commercially known means for synchronizing rotation of crank shafts are usable without departing from the scope of my invention.

55 If desired, the lubrication of my pump may be accomplished by several well known means of lubrication, for example, pressure lubrication by oil lines through the moving parts, with connections to external source of oil supply and outlets 60 into the various bearings.

With reference to the modified structure shown in Figures 4 to 6, it will be seen that cylinder 10a is provided with an inlet port 11a and a discharge port 12a as well as pistons 13a and 14a. 65 Piston 14a is connected to crank 16a by rod 18a and piston 13a is connected to rocker-shaft 44 by rod 17a. Portions 45 and 46 of crank shaft 16a are seated in bearings 62a and 63a and rocker shaft 44 has portions 47 and 48 seated in 63a and 64a. In this construction the extended end 39 of shaft 16a is provided for receiving suitable motivating power. Motion is imparted to rocker shaft 44 by means of side crank 49 on crank shaft 16a through link 50 to rocker arm 51 on rocker

shaft 44, thereby causing rocker shaft 44 to operate with a reciprocating action.

The operation of this modified structure is essentially the same as that of Figures 1 to 3, except that by means of this construction it is possible to effect more extensive control of the relative positions of the two pistons during the operating cycle than when driving each piston from a crank shaft. These effects may be accomplished by the selection of lengths of crank arms 10 on the rocker shaft driving the short stroke piston and a symmetrical or unsymmetrical combination of the arcs through which both crank arms of the rocker shaft travel, thus retarding or accelerating the motion of the piston driven from the rocker shaft with relation to the motion of the crank-driven piston during the various functions of the cycle.

Thus, when the device is used as a compressor, piston 13a may be caused to follow closely the motion of piston 14a during the first part of the cycle, thus minimizing vacuum effect prior to opening of the inlet port, and retarding the motion of piston 13a on the return stroke following closure of the inlet port, thereby permitting compression of the contents of the inter-piston space to or near the desired delivery pressure before opening of the discharge port.

Figure 6 is a representation of typical variations of inter-piston space during one complete cycle 30 of operation in a machine of the modified construction (Figures 4 and 5), in which, however, the coordination of piston movements with relation to the inlet and discharge ports is similar to that characteristic of the two-crank construction (Figures 1 and 2). In the diagram (Figure 6) the vertical scale indicates the face-to-face separation of the two pistons in percentage of the maximum. The horizontal scale represents one complete revolution of the long-stroke crank 40 in ten degree intervals. The zero point of the curve drawn on the diagram indicates the two pistons in virtual contact at the closure edge of the discharge port. The curve then shows gradual separation of the pistons to point 11 where the long-stroke piston uncovers the inlet port; continued separation to point 21, where the long-stroke piston covers and closes the inlet port; relative approach of the pistons to point 24, where the short-stroke piston uncovers and opens the discharge port; and continued reduction of inter-piston space during the remainder of the cycle, in which the material between the pistons is ejected through the discharge port, this action being completed at point 36, when the short-stroke piston covers and closes the discharge port, with the pistons again in virtual contact, moving in the same direction at momentarily uniform velocity.

This feature of complete delivery of the contents of the cylinder is a distinct improvement in the art of gas compression and vacuum pumping and it is possible with the construction herein described because of the absence of valves or passages communicating with the compression space. 65 Hence the device may be constructed to operate with zero volumetric clearance within the limits of mechanical accuracy.

What I claim as my invention is:

1. A pump having a cylinder provided with 70 inlet and outlet ports, two opposed pistons reciprocably mounted in the cylinder and controlling said ports, means for driving said pistons to effect differential movement of the pistons in a manner to increase the space therebetween when 75

the inlet port is open to draw fluid into the cylinder by the pistons and to effect movement of the pistons at different rates in a manner to compress the fluid, and discharge the same through the outlet port, and said means comprising cranks having different throws and respectively operatively connected to the pistons and means for driving the cranks at the same speed.

2. A pump having a cylinder provided with inlet and outlet ports, two opposed pistons reciprocably mounted in the cylinder and controlling said ports, means for driving said pistons to effect differential movement of the pistons in a manner to increase the space therebetween when the inlet port is open to draw fluid into the cylinder between the pistons and to effect movement of the pistons at different rates in a manner to compress the fluid, and discharge the same through the outlet port, and said means comprising cranks having different throws and different angular advances and respectively operatively connected to the pistons, and means for driving the cranks at the same speed.

3. A pump having a cylinder provided with inlet and outlet ports, opposed pistons reciprocably mounted in the cylinder for controlling said ports, means for reciprocating the opposed pistons in the cylinder in a manner that the pistons cooperate with one another to draw fluid into the cylinder therebetween during the interval the intake port is open and to compress the fluid and open the outlet port, said means comprising a pair of cranks having different throws with the

throw of one crank in advance of the throw of the other and means respectively operatively connecting the cranks to the pistons.

4. A pump having a cylinder provided with inlet and outlet ports, opposed pistons reciprocably mounted in the cylinder for controlling said ports, means for reciprocating the opposed pistons in the cylinder in a manner that the pistons cooperate with one another to draw fluid into the cylinder therebetween during the interval the intake port is open and to compress the fluid and open the outlet port, said means comprising a pair of cranks driven at the same speed and having different throws, the throw of one crank being in advance of the throw of the other and means respectively operatively connecting the cranks to the pistons.

5. A pump having a cylinder provided with inlet and outlet ports, opposed pistons reciprocably mounted in the cylinder for controlling said ports, means for reciprocating the opposed pistons in the cylinder in a manner that the pistons cooperate with one another to draw fluid into the cylinder therebetween during the interval the intake port is open and to compress the fluid and open the outlet port, said means comprising a pair of cranks driven at the same speed and connected together, said means having different throws with the throw of one crank in advance of the throw of the other and means respectively operatively connecting the cranks to the pistons.

GEORGE R. LYON.
